US00D816108S

(12) **United States Design Patent** (10) **Patent No.:** **US D816,108 S**
Fuller et al. (45) **Date of Patent:** **** Apr. 24, 2018**

(54) **DISPLAY SCREEN OR PORTION THEREOF WITH GRAPHICAL USER INTERFACE**

(71) Applicant: **Harman International Industries, Incorporated**, Northridge, CA (US)

(72) Inventors: **John Fuller**, Melbourne (AU); **George Yohng**, Vienna (AT); **Alex Semyonov**, Brest (BY); **Magnus Hornqvist**, Stenungsund (SE); **Michael Jago**, Melbourne (AU); **Danny Olesh**, Melbourne (AU)

(73) Assignee: **Harman International Industries, Incorporated**, Northridge, CA (US)

(**) Term: **15 Years**

(21) Appl. No.: **29/573,698**

(22) Filed: **Aug. 9, 2016**

Related U.S. Application Data

(60) Division of application No. 29/533,111, filed on Jul. 14, 2015, now Pat. No. Des. 774,076, which is a continuation of application No. 29/514,900, filed on Jan. 16, 2015.

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken line showing of the display screen, indicia, and other portions of the graphical user interface form no part of the claimed design.

1 Claim, 1 Drawing Sheet
